UNITED STATES PATENT OFFICE.

EMIL H. BENDEL, OF ALAMEDA, CALIFORNIA.

LETTERING-PEN.

1,359,865.

Specification of Letters Patent. Patented Nov. 23, 1920.

Application filed February 12, 1920. Serial No. 358,111.

To all whom it may concern:

Be it known that I, EMIL H. BENDEL, a citizen of the United States, residing at Alameda, in the county of Alameda and State of California, have invented certain new and useful Improvements in Lettering-Pens, of which the following is a specification.

My invention is an improved lettering pen.

The object of my invention is to provide a pen which will make a smooth, uniform line, regardless of the direction in which it is drawn, and which may be inserted in the ordinary pen holder.

Another object of my invention is to make a pen which may be cheaply and easily manufactured, in much the same way in which the steel pens are now made.

Referring to the annexed drawing which forms a part of this specification,

Figure 1 is a side view of my pen in a holder.

Fig. 2 is a bottom plan of the pen.

Fig. 3 is an end view of the pen point.

Fig. 4 is a top plan of the pen.

Fig. 5 is a side view of the pen.

Fig. 6 is a side view of the pen in writing position.

My pen may be made from a single piece of sheet metal, rolled into a shank 1 and a barrel-shaped pen point 2 extending downwardly at an angle of substantially 45 degrees to said shank. The pen point is preferably cylindrical in shape but may be of

other shapes. The pen point is provided with two diametrically opposed rear and front slots 3, at the sides of which are formed two diametrically opposed nibs 4. The ends of said nibs are bent inwardly at 40 right angles, forming end walls 5 of the pen point, a slot 6 being left between said walls extending diametrically of the point from one slot 3 to the other.

In writing the pen point assumes a vertical position with the end walls 5 resting flat upon the paper as shown in Fig. 6, and with the ink, which flows out of the point through slot 6, the pen writes a line of a width corresponding to the diameter of the 50 pen point.

Having described my invention I claim:

1. A pen including a shank and a barrel-shaped pen point, said point being provided with a rear slot and a front slot, and nibs 55 at the sides of said slots, the ends of said nibs being bent inwardly and providing therebetween a slot extending from the rear to the front of the point.

2. A pen including a shank and a barrel-shaped pen point extending downwardly from said shank, said point being provided with a rear and a front slot, nibs at the sides of said slots, the ends of said nibs being bent inwardly and providing therebetween a slot extending from the rear to the front of the point.

In testimony whereof I affix my signature.

EMIL H. BENDEL.
